UNITED STATES PATENT OFFICE.

JOHN D. WILLIAMSON, JR., OF PHILADELPHIA, PENNSYLVANIA, ASSIGNOR TO
WILLIAMSON BROS. CO., OF PHILADELPHIA, PENNSYLVANIA, A CORPORATION
OF PENNSYLVANIA.

ELECTRICAL STEERING-GEAR.

1,088,503.

Specification of Letters Patent.

Patented Feb. 24, 1914.

Application filed February 16, 1910. Serial No. 544,258.

To all whom it may concern:

Be it known that I, JOHN D. WILLIAMSON, Jr., a citizen of the United States, residing in Philadelphia, Pennsylvania, have 5 invented certain Improvements in Electrical Steering-Gears, of which the following is a specification.

One object of my invention is to provide a combination of apparatus, including an 10 electric motor, whereby the rudder of a vessel may be operated; it being particularly desired to provide a relatively simple means for controlling the starting and stopping of such motor.

15 I further desire to provide an electrical steering gear having the above noted characteristics, in which the motor controlling switch or switches may be manually moved to start the motor and automatically 20 returned to the off position after said motor has operated to a predetermined extent.

Another object of the invention is to provide an electrical steering gear which shall include a motor controlling switch manually 25 operated to start the motor and returned by the motor itself to its off position, which switch has in connection with it some means for preventing a breakage of the motor current at certain of its contacts, and is also so 30 constructed as to prevent damage to the motor or to any of the controlling devices owing to improper manipulation of the hand controlled apparatus.

These objects and other advantageous 35 ends I secure as hereinafter set forth, reference being had to the accompanying drawings, in which:—

Figure 1, is a plan, partly in section and to some extent diagrammatic, showing a 40 combination of apparatus arranged according to my invention; Fig. 2, is a side elevation of the apparatus shown in Fig. 1; Fig. 3, is a side elevation, partly diagrammatic, illustrating a modified form of my invention; Figs. 4 and 5 are respectively a partly 45 diagrammatic side elevation and a partly sectional plan of another modification of the motor controlling means; Fig. 6, is a diagram of the connections of the apparatus 50 shown in Fig. 4; Figs. 7 and 8 are respectively a side elevation and a partly sectional plan of a further modification, and Fig. 9 illustrates another form of my invention.

In the above drawings, 1 is a drum on

which are wound the cables or chains connected to the head of the rudder and said drum is mounted on a shaft carried in bearings on a frame 2; there being fixed to it a worm wheel 3 and a spur gear 4. Engaging the worm wheel is a worm 5 fixed on the 55 armature shaft of a motor 6 designed to provide the power necessary for operating the drum. The frame 2 also has a bearing for the support of a longitudinally movable shaft 7 forming part of a floating mechanism including a relatively narrow faced gear 8 meshing with the broad gear 4, and a nut 9 revolvably mounted in a bearing 10 but held thereby from longitudinal movement. Said shaft has a threaded portion 70 passing through this nut and has fixedly mounted on it a collar 11 engaged by the forked end of a lever 12 fulcrumed on the frame 2 and constituting a floating member. The nut has connected to it (integrally 75 in the present case) a beveled gear 9^a designed to mesh with a second beveled gear 13 mounted on a vertical shaft 14 which is directly operated from a hand steering wheel 14^a. The lever 12 is connected 80 through a link with a pair of contact arms 15 and 15^a, or as in Figs. 4 and 5, is itself constructed to serve as a contact arm designed to co-act with two series of contacts 16 and 16^a mounted on a slab 17 of insulating material and connected to different points of a body of starting or controlling resistance 18, which in turn is connected in circuit with the armature of the motor 6 in the manner well known to those skilled in 85 the art.

With the above described arrangement of parts and the motor and rheostat suitably connected to a source of current, a turning of the hand steering wheel will turn the 95 shaft 14, and through the bevel gears 9^a and 13, turn the nut 9. As a consequence, the shaft 7 and with it the collar 11, is caused to move longitudinally so that the lever 12 is turned on its fulcrum and moves the contact arms to one side or the other of their central position, thus bringing them into engagement with the contacts so as to supply current to the motor and start the same. The operation of the motor turns the worm 100 5 and the worm wheel 3, thereby also turning the drum 1, and through the cables wound upon or delivered therefrom, alter-

ing the position of the rudder to which said cables are connected. The operation of the motor, however, also turns the gears 4 and 8 and thus turns the screw shaft 7 in such 5 a direction that this is forced to move through the fixed nut 9 in a direction which gives to the collar 11 and lever 12 a motion the reverse of that originally given them. The lever thus gradually returns the contact arms to their off positions, cutting current off from the motor, which is thus permitted to come to rest. Further operation of the shaft 14 by the steering gear causes another operation of the motor and its subsequent automatic stoppage, so that the rudder may be brought to any desired angle 10 relatively to its normal position or may be returned to such position as desired.

For reversing the direction of rotation of 20 the motor armature there is provided a central contact piece 19 permanently connected to one of the current supply mains, and the two contact arms are respectively connected to the two armature terminals;—one terminal 25 of the rheostat being connected to the second supply main while the field winding of the motor in this case is separately excited. As a consequence, the motor armature turns in one direction when the contact 30 arms are moved to one side of their central position and in an opposite direction when said arms are moved to the other side; the contact arms and contacts acting as a reversing switch. If desired, this starting 35 and reversing switch may be made to control an auxiliary switch whereby the armature circuit of the motor is kept open until the arms 15 and 15^a have fully engaged the contacts 19 and 16 or 16^a, as the case may 40 be, and is broken before said contact arms are moved out of engagement with their contacts. For this purpose, I may employ a combination of apparatus such as is shown 45 in Fig. 3, in which I mount on the rheostat slab 17 a pair of auxiliary contacts 20 in position to be engaged by special contacts 21 on the arms 15 and 15^a when these are moved to either side of the mid or off position. Both the contacts 20 are connected to each 50 other, as are also the contacts 21; these latter being also connected to one end of the winding of a solenoid 22, whose second end is connected to one current supply main while said contacts are connected to the second 55 main. The core of the solenoid is attached to the movable member 23 of any desired form of switch, illustrated in Fig. 6, as of the mercury type, which is connected in the main motor circuit. With this 60 arrangement of parts, the first movement of the arms 15 and 15^a from their "off" position brings one of the contacts 21 into engagement with one of the contacts 20, thereby permitting current to energize the 65 solenoid, which is so designed that when

so energized it closes the switch to which its core is connected and thus completes the armature circuit of the motor. By the time, however, that this solenoid-controlled switch has closed the armature circuit, one of the 70 arms 15 has engaged one set of the contacts 16, while the other has engaged a contact plate 19, thereby permitting current to flow to the armature of the motor through a body of resistance whose amount depends upon 75 the extent of the displacement of the arms 15 and 15^a from their off position. In this case, as well as in that previously noted, it will be seen that the connections are such that the contacts on the slab or plate 17 constitute a reversing switch.

If desired, the apparatus used in Figs. 4, 5, and 6 may be employed, according to which arrangement the lever arm 12^a connected to the collar 11 itself acts as the contact arm of the rheostat and at the same time controls a switch, in this case of the double-throw, three-pole type, whereby the direction of the current flow to the armature of the motor is controlled, as is also the 85 switch governing the current flow through the solenoid 22. For this purpose the parts are so arranged that through the medium of a link 12^b, a lever 25 is rocked on its fulcrum when the contact arm 12^a is moved 90 by the collar 11, so that three of the contacts 30, 30^a, 31, 31^a, 32, and 32^a are moved into or out of mercury cups or other suitable fixed contacts. Of these cups and contacts, the first four pairs are connected to form a 95 reversing switch for the motor, while the last pair is arranged to form a switch in circuit with the winding of the solenoid 22. With this arrangement of parts, the displacement of the contact arm from its central 100 position closes two sets of contacts of the reversing switch and at the same time closes the circuit of the solenoid winding so that this latter acts to close the switch which it controls, as described in connection 105 with Fig. 3, and thereby makes the final closing of the armature circuit. In order that damage may not result from such a small displacement of the contact arm 12^a as would be insufficient to start the motor, 110 I connect across the line the winding of a second solenoid 33, so that this is energized as soon as current is turned on to the apparatus by such a displacement of the contact arm as would bring it into engagement with 115 the first of the contacts of the rheostat. This solenoid controls an automatic rheostatic switch which includes a series of contacts 33^a connected to various points of the resistance 18, an elongated contact 33^b, and 120 a bridging piece at all times engaging the latter contact while being capable of engaging any of said contacts 33^a. This bridging piece 33^c is fixed to the core of the solenoid, 125 so that when the latter is energized in the 130

5 manner well known in the electrical art, it serves to automatically start the motor, thus causing this latter to operate to the desired extent and then bring itself to rest by rotating and longitudinally moving its shaft with the collar 11, with the resultant moving of the contact arm to its off position, as heretofore described.

10 The apparatus shown in Figs. 7 and 8 is so arranged that the switch for controlling the flow of current through the winding of the solenoid 22 is mounted on the slab 17, and as in the case illustrated in Fig. 4, the reversing switch with the circuit controlling 15 solenoid is external to said slab.

In that form of switch shown in Fig. 9, I connect to the arm 12 which is controlled by the collar 11, a cross head 35 mounted to slide upon a pair of bars A and B, each of 20 which is divided into several parts electrically insulated from one another. In the structure shown, the bar A has three active parts a , a' , and a'' , of which the latter is permanently connected to one of the current 25 supply mains. The second bar B has five active parts of which those at its extremities, indicated at b^1 and b^2 , are electrically connected to each other and to the second current supply main. The cross head 35 includes 30 two transverse bars each consisting of two parts insulated from each other, the parts 35^a and 35^b being slidable on the bar A and the parts 35^c and 35^d being slidable on the bar B. The two latter of these parts 35 of the crosshead are respectively connected to the terminals of the motor armature while the parts 35^a and 35^b have contact brushes 50 and 51 placed to engage the contacts 16 and 16^a mounted on a suitable supporting 40 structure. The armature resistance 18 is connected to these contacts in the customary manner and has one of its ends connected to the part b^2 of the bar B. As before, any displacement of the lever 12 to either side of 45 its off position, moves the crosshead 35 so as to start the motor, whose operation actuates the rudder and brings said crosshead back to its off position, with consequent stoppage of the motor. In this case I have provided 50 the collar 11 with a projecting tooth and have placed a coöperating tooth on the rotary nut 9 of the beveled gear 9^a , so that after the rotation of said nut has moved the shaft with said collar a predetermined distance in one direction, said teeth come into engagement to prevent further movement thereof or jamming. Similarly the gear 55 wheel 9^a has on its opposite side a second tooth designed to coöperate with a tooth on the adjacent end of the shaft to prevent excessive movement or jamming when said shaft is turned a predetermined distance in the opposite direction.

I claim:

65 1. The combination of a member con-

nected to a device to be actuated; an electric motor for operating said member; and controlling means for said motor; said means including an electric starting switch; hand operated means for moving said switch from its off position to start the motor; means connecting the switch with the motor for automatically returning it to its off position; an automatically acting switch for starting the motor independently of said first starting switch after the latter has been moved from its off position; and a switch actuated by said hand operated means for controlling said automatic switch.

2. The combination of a member connected to a device to be actuated; an electric motor for operating said member; and controlling means for said motor; the same including a starting switch; hand operated means for moving said switch from its off position to start the motor; means connecting the switch with the motor for automatically returning it to its off position; and a reversing switch mechanically connected to 90 said starting switch.

3. The combination of a member connected to a device to be actuated; an electric motor for operating said member; and a rheostatic switch for controlling the starting of the motor; said switch including a 95 member operative both by hand and by said electric motor; with an automatic motor starting device connected to start the motor independently of said rheostatic switch after this has been moved from its off position.

4. The combination of a member connected to a device to be actuated; an electric motor for operating said member; a floating member; hand operated means for actuating 105 said floating member; means for connecting the floating member to the motor for automatically returning it to its off position after it has been moved therefrom by hand; a starting switch directly operated by said floating member, and a motor reversing switch mechanically connected to said floating member.

5. The combination of a member connected to a device to be actuated; an electric 115 motor for operating said member; a controlling switch for the motor; a floating member movable by the motor for returning the switch to its off position; means for operating the floating member by hand independently of the motor; with a switch controlled by the floating member and having means for closing the motor circuit after the starting switch has been closed and for breaking the motor circuit before the starting switch 125 is opened.

6. The combination of a member connected to a device to be actuated; an electric motor for operating said member; a controlling switch for the motor; a floating member 130

movable by the motor for returning the switch to its off position; means for operating the floating member by hand independently of the motor; an electromagnetic switch connected to close the motor circuit after the controlling switch has been closed and to break said circuit before the controlling switch is opened; with auxiliary contacts controlled by said floating member for

governing the actuation of said electro-magnetic switch. 10

In testimony whereof, I have signed my name to this specification, in the presence of two subscribing witnesses.
